DISPLAY CONTAINER FOR POCKET HANDKER-
CHIEFS OR SIMILAR ARTICLE

Joseph M. Gindi, Brooklyn, N. Y.

Application April 14, 1955, Serial No. 65,522

Term of patent 14 years

(Cl. D30--5)

Fig. 2

Fig. 1 is a front perspective view of a display container for pocket handkerchiefs or similar article, showing my new design.

Fig. 2 is a sectional view of the display container for pocket handkerchiefs or similar article shown in Fig. 1 taken along lines 2—2 of Fig. 1.

I claim:

The ornamental design for a display container for pocket handkerchiefs or similar article, as shown.
